[57] **CLAIM**

The ornamental design for a device for extracting soil cores for laboratory analysis, substantially as shown.

DESCRIPTION

FIG. 1 is a front elevation view of a device for extracting soil cores for laboratory analysis showing my new design;

FIG. 2 is a side elevation thereof seen from the left side of FIG. 1;

FIG. 3 is a side elevation thereof seen from the right side of FIG. 1;

FIG. 4 is a rear elevation thereof;

FIG. 5 is a top plan view thereof;

FIG. 6 is a bottom plan view thereof; and

FIG. 7 is a top perspective view thereof showing the device in open condition.

Fig. 2.

Fig. 1.

Fig. 3.

Fig. 4.

Fig. 6.

Fig. 7.
